UNITED STATES PATENT OFFICE

WILLEM VOORWINDE, OF ROTTERDAM, NETHERLANDS

GRAB

Application filed March 4, 1931, Serial No. 520,014, and in the Netherlands March 12, 1930.

The invention relates to an automatic grab for controlling, i. e. regulating the closing force of automatic grabs with two jaws hinged together, said jaws being closed by means of one or more cables.

It is known that for working rough material, for instance ore, the closing of the automatic grab requires a force greater than the force wanted for working for instance sand or corn. For this reason, in the first case cables with more blocks or more rollers will be used than in the second case. If one and the same grab is used for both purposes, then always the difficulty has to be overcome that the grab takes either not enough in the case of rough material, or too much when working fine grainy material. The insertion of further rollers or putting them out of service for the purpose of modifying the closing force takes up much time, especially because the cables to be inserted or to be eliminated are very thick and stiff.

The invention aims to render possible the execution of this changing in a shorter time and consists in principle in laying one or more portions of the cable in the form of a loop over an appropriate support or fulcrum of the grab, thus putting this portion or portions wholly or partially out of action. As the length of a thus guided part stays unvariable during the closing of the grab or varies less than under normal circumstances, that portion will play no part or only a smaller part for determining the closing force.

The annexed drawings show diagrammatically an automatic grab, by way of example.

Fig. 1 is a side view of a closed grab; and Fig. 2 is a side view of an open grab according to the invention, whilst

Fig. 3 is a front view, partially in vertical section.

The automatic grab consists of two jaws 5 and 6, fixed together by a hinge-like joint. The closing rope 7 runs in a known manner through a hole in the head or top shaft 4, then over a guiding roller 8 near to said top shaft, further over a pulley 9 of one of the jaws 5 and then round a pulley 10 of the

other jaw 6 to a fixed point 11 of the first-mentioned jaw 5.

The second closing rope 12, Fig. 3, within the grab, has not been illustrated for clearness sake. This cable or rope runs in a similar manner over the pulleys of both jaws and is fixed to a fixed point of the jaw 6. Of course, each cable, instead of running over only two pulleys, can run over a plurality of pulleys.

For the purpose of putting a portion of the rope or cable between the pulley 10 and the fixed point 11 out of action, a saddle-shaped support 13 is rigidly fixed under the head shaft 4, at a short distance therefrom.

As can be seen from Fig. 2, it is necessary to lift the above-mentioned portion very little if the grab is in open position, for the purpose of laying said portion of the rope upon the support 13.

The normal position of the cable is indicated by a dot and dash line, whilst the portion out of action is indicated by a dotted line.

As can be seen from Fig. 3, the pulleys 9 and 10 and also the fixed point 11 are arranged in vertical planes spaced apart from one another, so that the rope or cable portions run without touching one another.

The saddle-shaped support will be preferably mounted and executed in such a manner that the length of the portion of the rope laying on said support, thus between the fixed point 11 and the point where that portion leaves the pulley 10, will be equal to the distance between the point 11 and the axis of the top shaft 4, increased with the length of the tangent from that axis to the pulley 10. This length will stay unvaried during the closing of the grab, so that the portion will then be wholly put out of action.

If this prescription is not satisfied, the portion of the rope or cable will only be partially put out of action.

Now it is possible to still more exactly determine the closing force, if the position of the guide-roller 8 may be changed in vertical direction, or if one or more fixed supports for the portions of the rope or cable are

mounted to one or both jaws of the grab, between the head shaft and the tackle.

In this case, however, it is recommended to execute the support in the shape of a rotatable pulley 13', for avoiding the rubbing of the cable over its support.

Of course, a separate adjustable support may be provided for each portion of the cable, and said support may be rotatably mounted.

I claim:

1. In an automatic grab, the combination of two jaws, a hinge-like joint connecting together said jaws, at least one cable carrying 15 said grab, at least one pulley on each jaw, one portion of the cable running over said pulleys and fixed to a fixed point of one jaw, and a support on the grab for supporting that portion of the cable between the last pulley 20 and said fixed point, for the purpose set forth.

2. In an automatic grab, the combination of two jaws, a hinge-like joint connecting said jaws together, at least one cable for operating 25 said grab and its jaws, at least one pulley on one jaw, a fixed point for attaching the end of the cable at the other jaw, at least one support for one portion of the cable, said support being mounted in such a manner that 30 the length of the portion of the cable laying on said support is equal to the distance between said fixed point and the hinge-like joint increased with the length of the tangent from that hinge-like joint to said pulley.

35 In testimony whereof I signed hereunto my name.

WILLEM VOORWINDE.
